UNITED STATES PATENT OFFICE.

EMIL P. STARY, OF CEDAR RAPIDS, IOWA.

INTERNAL-COMBUSTION ENGINE.

1,318,619.

Specification of Letters Patent.

Patented Oct. 14, 1919.

Application filed April 14, 1919. Serial No. 289,843.

To all whom it may concern:

Be it known that I, EMIL P. STARY, a citizen of the United States, residing at Cedar Rapids, in the county of Linn and State of Iowa, have invented a new and useful Internal-Combustion Engine, of which the following is a specification.

This invention relates to internal combustion engines, the object of the invention being to provide an engine of this type in which one or more cylinders are caused to rotate bodily around an axis and having pistons adapted to reciprocate within said cylinders.

A further object of the invention is the provision of improved means for causing the reciprocation of the pistons within the cylinders.

A further object of the invention is to provide means for preventing the withdrawal of the pistons from the cylinders, whereby the cylinders are caused to rotate.

A further object of the invention is to provide an engine of the character set forth, whereby a smoother running engine is obtained than heretofore and which is extremely economical in operation, for the reason that greater power is obtained with less fuel.

With these and other objects in view, which will appear as the description proceeds, the invention consists in the novel features of construction and combination of parts, all of which will be more fully described hereinafter and finally pointed out in the claims.

The drawing accompanying and forming part of this specification illustrates an end view of the housing of an engine in which is embodied my invention.

In the embodiment of the invention herein illustrated, 2 designates the frame or housing of an engine, in which is mounted for rotation a driving shaft 3 for transmitting power from the cylinders to the working parts of the engine. To the shaft 3 is secured an arm 4 which extends across the housing 2 and carries at each end thereof a cylinder 5 firmly secured thereto, the cylinders having pistons 6 adapted for reciprocation therein.

For the purpose of reciprocating the pistons, I have provided a system of levers adapted to be operated by means of cam-formed track guides. In the present instance a bell crank lever 7 is pivoted between

a pair of lugs or ears 8 carried by the cylinder. One arm of the bell crank is pivoted at its end to the piston rod 9, while the other arm of the bell crank carries at its free end a roller 10 for a purpose to be presently described. Secured to the housing 2 is a system of cam track guides, shown herein as formed of a pair of inner members 11 and 12 located at opposite sides of the axis of rotation of the shaft 3 and each extending a distance equal to approximately one-fourth of the length of the path of travel of the cylinders, and an outer member 13 also extending approximately one-fourth of the length of the path of rotation of the cylinders, the member 13 being located opposite one of the gaps formed between the ends of the members 11 and 12. The track guides 11, 12 and 13 are eccentrically disposed with relation to the path of travel of the cylinders and also with relation to each other, as shown in the drawing.

Secured to the housing 2, at the exterior thereof, is a flat spring 14 having secured thereto at its free end a plunger 15 which projects through an opening in the housing 2 into the path of the outer end of the piston rods 9 at the proper point with relation to the track guides 11, 12 and 13. The plunger 15 is provided with an inclined surface 16 over which the piston rod is adapted to ride and the longer end of which is adapted to form a stop for preventing the piston from being forced outwardly under the force of the explosion, as hereinafter described.

In the operation of the engine, the cylinders being in the position shown in the drawing, the cylinder at the lower portion of the figure is at the point in its travel where the charge is under compression, the spark being set to ignite the charge at this point. In this position the end of the piston rod abuts against the spring-pressed plunger 15 so that when the explosion takes place the piston is held against withdrawal from the cylinder and the latter is thereby caused to rotate in the direction shown in the drawing. This rotation carries the roller 10 into contact with the outer face of the track guide 11, which, by reason of its cam action on the roller, forces the piston inwardly, the piston reaching the limit of its innermost movement just as the roller passes out of engagement with track 11. The roller 10 then engages the inner face of the track

13 and is gradually forced toward the axis of rotation of the arm 4, thereby withdrawing the piston and drawing a charge into the cylinder. When the roller 10 has 5 reached the end of the track 13 the piston has reached the limit of its outward stroke and the roller then passes into engagement with the outer face of the track guide 12, which again forces the piston inwardly, 10 thereby compressing the charge in the cylinder. When the roller has reached the end of this track 12 the charge is fully compressed and the outer end of the piston rod has passed over the spring-pressed plunger 15 and is thereby locked against withdrawal, whereupon the above described operation is repeated.

It is believed unnecessary to show herein the carburetor and ignition system, since 20 these features are well understood. If desired, the arm 4 may be so constructed as to form the gas and exhaust manifold.

While I have described in detail the structure herein illustrated, I do not desire to limit my invention to the precise features 25 of construction shown, as I am aware that many mechanical changes may be made without departing from the spirit and scope of the invention as set forth in the appended 30 claims.

Having thus described my invention, what I claim is:

1. In an internal combustion engine, a stationary circular casing, traveling cylinders supported within the casing, track 35 guides eccentrically disposed with relation

to the path of travel of the cylinders, a shaft extending through the casing, an arm operating on the shaft, said arm having connection with the cylinders, pistons in the 40 cylinders, piston rods connected to the pistons, bell crank levers having connection with the piston rods, a roller on one extremity of each bell crank lever and operating on the track guides, and a spring pressed 45 lug extending through the casing and co-operating with the piston rods for preventing rotary movement of the cylinders, in one direction.

2. In an internal combustion engine, a 50 stationary circular casing, traveling cylinders within the casing, each of said cylinders having integral lugs, a bell crank lever pivoted to each of said lugs, pistons in the cylinders, said pistons having connection 55 with the bell crank levers, means on the opposite ends of the bell crank levers for engaging the inner wall of the casing, for causing movement of the pistons, a spring pressed plunger having an inclined surface, 60 extending through the casing, and within the path of travel of the cylinders, said plunger adapted to coöperate with the cylinders for preventing rotary movement of the cylinders in one direction. 65

In testimony that I claim the foregoing as my own, I have hereto affixed my signature in the presence of two witnesses.

EMIL P. STARY.
